Straw Cutter.

Patented Aug 2, 1808.

Otis Holabird's.

Sellers Patent. April 2, 1868.

The Schedule referred to in these Sellers Patent and making part of the same containing a description in the words of the said Otis Holabird himself of his Machine for cutting Straw.

The frame is composed of scantling or slate work three inches by four. three feet high by three feet in length, and fifteen inches wide from inside to inside. The plates project six inches in front. On the top of the projection is placed the crank or spindle of the frame. The side gutters are framed into the posts six inches below the plates, under which 5 inches from the front post is placed the lower cylinder and is confined by a box at each end for the quidgen to turn in. The upper cylinder has its box to turn in cut through the sides of the straw box, in such a manner as to rise or sink according to the quantity of straw in the box, and is kept to a proper bearing or pressure on the straw by springs placed over the quidgen and fastened to the underside of the plates. On one end of both cylinders outside of the straw box are fastened cog wheels containing ten spurs each two inches in length out of the rim of the wheels which are five inches and a half diameter. Each cylinder within the straw box is seven inches in diameter. The under one is operated upon a pivot in motion by the upper one by means of a ratchet like those in common looms, with a holding and feeding hand. The feeding hand is made with a joint which effects the rolling of the cylinders by the rising of the knife gate, and the gate rises by turning the crank with a sweep radius of 12 inches. Upon the centre of the knife gate is a spur bent in the shaft of the crank of 2 1/2 inches which raises the gate 5 inches by a pinion extended from the shaft to the lower part of the gate. On the opposite end of the crank shaft is a balance wheel three feet in diameter, with four arms, and the arms three inches wide and three inches thick. One only under the lower part is fitted to which is fastened the Red knife, the lower gate hook and the other is formed by a groove in the plate. The upper knife is secured to the lower part in the gate, sloping two inches in thirteen. The operation

of the knives in cutting straw is similar to that of Shears, or the Guillotine and the straw is conveyed to the knives by the rolling of the cylinders. The bottom or floor of the box that contains the straw is an inclined plane of 8 inches in five feet. The sides are thirteen or fourteen inches wide at the gate and 9 inches at the other end and are five feet long and thirteen inches wide.
